UNITED STATES PATENT OFFICE.

PHILIP L. O'DONNELL, OF CINCINNATI, OHIO.

TAPING MACHINE.

Application filed September 11, 1923. Serial No. 662,134.

My invention relates to machines for applying tape to shoes, this operation being an essential part in the manufacture of the uppers of a good many styles of these articles.

I have set forth in a copending Patent No. 1,556,124, dated Oct. 6, 1925, the generic machine elements and process, of which this invention is a refinement.

10 It is my object in the present invention to provide a machine which can be used for applying tape to a piece of leather or other fabric, for re-inforcing or edging or other purposes, and which tape carries its own heat plastic binding agent by means of which it is applied.

My mechanism includes a device for taking off the tape from a spool or roll thereof, and device for heating the tape, in order to

20 make soft, adherent and plastic, a cementitious coating thereon. It has a feeding mechanism for feeding a piece of material to be taped along with the tape, and at the same time permitting the manipulation of 25 the work being fed so that it can be turned about, as in sewing a seam with a sewing machine.

I have discovered that if an attempt is made to employ the work feeding mechanism to draw a piece of cement faced tape 30 through a heater, from a spool or other storage, in machines of the character herein, that uniformly good results cannot be had. I accordingly have worked out a particular 35 method and mechanism for mounting and taking off the tape, which is adjustable to suit different conditions.

I have also found that a simple sewing machine feed for the work in the absence of 40 a pressure member which comes down on the work and travels with it, along with the underneath feed dog, will not give the best results, or permit of the desired manipulation of the work.

45 I have also arranged a particular device for holding the tape on the feed table or closely adjacent thereto, so as to obtain the greatest control on the action of the machine in following the required curves in a piece 50 of work.

Prior to this invention and my allied invention, upon which application has been filed, as above set forth, I am not aware of any one having successfully applied heat

plastic tape in the manufacture of shoes 55 by means of a machine which unites the tape to the article as it is attached thereto. This work is universally done with a tape to which cements are manually or mechanically applied which requires much skill, in 60 avoiding staining of the article being treated.

I accomplish my object above set forth by that certain construction and arrangement of parts to be hereinafter more specifically 65 pointed out and claimed.

In the drawings:

Figure 1 is a front elevation of my machine.

Figure 2 is a top plan view thereof.

Figure 3 is a side elevation thereof.

Figure 4 is a perspective of the feed table, tape guide.

Referring to the mechanism shown by way of illustration of my invention, I have 75 not attempted to show the full details of all parts, as some of them are in common use in sewing machines, and have been for many years.

Thus I show a frame 1, mounted on a 80 table 2, and operated by a motor 3. On the frame is a small feed table 4, having an opening therein through which extends the feed plate 5. This plate has a roughened surface, and is driven by a cam 6, so as to rise through the table opening slightly, move transversely of the opening and then sink down away from the table and around to rising position again, through a rapid succession of continuous cycles of movement. 85 Also a crank 7 on a shaft 8 is linked with the feed plate to enforce parallelism of movement. 90

The motor drives the presser foot shaft 9 by means of a belt and pulley 10 and 10^a 95 respectively. From a crank on the shaft 9 is a connecting rod 11 which engages link 12 on the shaft 8 for the crank 7, and also engages a crank 12 on the shaft 13, said last noted shaft having the cam 6 thereon.

The presser foot shaft drives an eccentric stud 14, to which is connected the link 15, same being pivoted on a pin 16 held fast in the arm 17. This arm has a nose 18 to be engaged by a lift 19, and has a pivoted arm 20 that engages by clamping over the presser foot rod 21. A spring 22 on the presser foot rod 21 is engaged by this arm 120

20, and by the casing at the top of the machine, through which casing is slidably set the end of the rod 21.

By this means the presser foot rod is operated, so as to be lifted, and having a spring return to depressed position. The presser foot itself is a slotted member 23 on the end of the rod 21. The fulcrum in the lifting operation is the walking foot where it contacts with the work table.

The walking foot is shown at 24, and rests in the slot of the presser foot, and is mounted on a rod 25. This rod 25 is pivoted at 26 to a link 27, this link being connected 15 to the same pin as that which connects the clamping arm 20 with the arm 17.

As so constructed the operations of the walking and foot and presser foot are as follows, starting with the parts as in Figure 3. The eccentric at the top of the machine revolves, thereby rocking the arm 17 and with it rocking the link 27, with the result of rocking the end of said link that is pivoted to the rod 25 downwardly. When 25 the foot 24 contacts with the feed plate, which is timed to start its feeding movement as the walking foot comes down against it, the pivot at 26 will permit the said foot to travel along with the feed plate. Also when 30 the foot comes into contact with the feed plate, the pivot at 26 can no longer move downwardly, which forces the arm 17 to rise, carrying with it the arm 20, and the presser foot rod 21, the link 27 swinging upwardly.

This happens during the first quarter turn of the eccentric at the top of the machine, and as the eccentric continues, the spring will first force the presser foot down again, 40 holding whatever happens to be under it, against the table, and the walking foot is then raised, as soon as the presser foot comes down, whereupon the walking foot is thrust forward by the spring 27*, ready for its 45 next step.

This motion is not novel with me, but is to be found in sewing machines having a walking foot and a presser foot cooperating with a feed plate, and the result of the feeding action is to advance a piece very rapidly by short steps, in fact so rapidly that in the usual operation the motion seems continuous.

For mounting a roll of tape I provide a 55 shaft 30, bent down at 31, and adjustably held by a clamping screw 32, in a standard 33. The roll of tape 34 may thus be mounted like a spool on this shaft 30, and the height of the shaft with relation to the 60 base of the machine can be adjusted.

Mounted on standards 35, 35, is a rotary shaft 36, having a pulley 37 thereon, that receives its motion from the shaft 13, through the medium of a belt. The shaft 65 36 lies between the tape spool and the heater

device, so that the tape must pass over it, with the tension of the tape, i. e. the amount thereof that has surface contact with the shaft 36 being adjusted by movement of the spool up or down.

In the base 2 of the machine is a slot 40, through which the tape passes. This slot lets into a heating duct, which in the example shown is L-shaped, and formed of a square tube 41, having idler rolls 42, located 70 therein so as to guide the tape and give it an anti-friction passage through the tube. An electric heater unit 43 is shown which applies heat to the tube 41.

This tube 41 extends up through the base 80 to a point fairly close to the feed table, where it emerges from the tube and passes over a roller 44, and thence through a holder and guide piece 45. This guide piece lies just forwardly of the engaging point of the 85 feed plate, and may be formed of a piece of flat metal bent to form a narrow horizontal opening, and screwed down to the table as at 46.

My process then proceeds as follows: The 90 operator lowers the lift 19, so as to permit the presser and walking feet to come into operation, having first fed the tape through the guide, and underneath the presser foot. He then turns on the heat, and runs enough 95 of the tape through the machine by starting the motor, to be sure that the heat has rendered the plastic coating thereon into a soft, adhesive stage. He then takes a piece 100 of work, such as a shoe upper, and feeds it under the presser foot and walking foot, operating the machine at the same time. The operation will then result in causing the tape to adhere along the line of feed of the 105 piece of material, to the underface of same, as it is fed.

I find that it is absolutely essential to have the tape feed shaft 36, to help the feed of the tape, as if it were merely pulled along by the action of the work feed, it will break, and cause much loss of time. I find it essential to use a combination of feed plate, walking foot and presser foot, so that the action on the tape is correct, and of course, the heater must be employed to make the tape 115 plastic and adherent. The small guide plate, close to the work is also a necessary feature, as it prevents curling, and gives the correct tension on the tape, keeping it from running slack, and bunching up or wrinkling on the 120 work.

By the use of my invention in the taping of shoes, I find that five persons can do the work of around twenty, and that the piece-work rates can be cut down to one sixth of the hand work cost, with higher daily wage to the worker than by the hand system.

Having thus described my invention, what I claim as new and desire to secure by Letters Patent; is:—

1. A mechanism for the purpose described, comprising a tape mounting device, a rotary feed element, over which the tape must pass, a heater with relation to which the tape is guided, and a work feeding device comprising a feed plate arranged to come in contact with the work during a portion of a cycle of movement, and a walking foot and presser foot adapted to contact with the feed plate, and means for guiding said tape from the heater to the said work feeding device. 45
2. A mechanism for mounting and feeding a heat plastic tape to a work feed wherein it is to be fed along with a piece of work and caused simultaneously to adhere thereto, comprising a storage mechanism for the tape from which it can be withdrawn, a feeding device formed of a continuously driven rotary member over which the tape must pass 50 after leaving the storage mechanism, a heater with relation to which the tape is guided, and means for guiding the tape to the work feed, where it is fed along with the work to which it is to be attached said work feed of 55 a type to intermittently advance the tape and work. 60
3. A mechanism for mounting and feeding a heat plastic tape to a work feed wherein it is to be fed along with a piece of work and caused simultaneously to adhere thereto, comprising a storage mechanism for the tape from which it can be withdrawn, a feeding device formed of a driven rotary member over which the tape must pass after 65 35 it leaves the storage mechanism, a heater with relation to which the tape is guided, and means for guiding the tape to the work feed, where it is fed along with the work to which it is to be attached, said guiding 70 40 means comprising a member lying close to the work feed, and forming a flat, restricted aperture through which the tape must pass. 75
4. A mechanism for mounting and feeding a heat plastic tape to a work feed, wherein it is to be fed along with a piece of work to which it is simultaneously caused to adhere, which consists, in a heater through which the tape passes, a guide adjacent to the work feed, and presenting a flat narrow aperture through which the tape must pass, 80 a storage reel for the tape, and driven rotary means acting between the storage reel and the heater for imparting a feeding movement to the tape. 85
5. A mechanism for the purpose described, comprising a tape mounting device, a rotary feed element over which the tape must pass, a heater through which the tape is guided, and a work feeding device comprising a feed plate arranged to come in contact with the work during a portion of a cycle of movement, and a walking foot and presser foot adapted to contact with the feed plate, and means for guiding said tape from the heater to the said work feeding device, said means comprising a member having a flat restricted aperture through which the tape must pass, to hold it taut in the work feed. 90
6. A mechanism for mounting and feeding a heat plastic tape to a work feed wherein it is to be fed along with a piece of work and caused simultaneously to adhere thereto, comprising a storage mechanism for the tape from which it can be withdrawn, a feeding device formed of a driven rotary member over which the tape must pass after leaving the storage mechanism, a heater with relation to which the tape is guided, and means for guiding the tape to the work feed, where it is fed along with the work to which it is to be attached, said heater formed of a tube, a heating element applied to said tube, and rollers in the tube to provide an anti-friction path for the tape there-through. 95
